CLAIM

The ornamental design for a combined pipe lighter holder and tools as shown and described.

DESCRIPTION

FIG. 1 is a front perspective view of the combined pipe lighter holder and tools;

FIG. 2 is a front elevation view of the combined pipe lighter holder and tools;

FIG. 3 is a back elevation view of the combined pipe lighter holder and tools;

FIG. 4 is a right elevation view of the combined pipe lighter holder and tools;

FIG. 5 is a left elevation view of the combined pipe lighter holder and tools;

FIG. 6 is a top plan view of the combined pipe lighter holder and tools;

FIG. 7 is a bottom plan view of the combined pipe lighter holder and tools; and,

FIG. 8 is a rear perspective view of the combined pipe lighter holder and tools.

(Continued)

Features shown in evenly dotted broken lines illustrate portions of the combined pipe lighter holder and tools that form no part of the claimed design.
